United States Patent Office

Des. 212,090

Patented Aug. 27, 1968

212,090

FILTER

James R. Edmiston, Sherman Oaks, Calif., assignor to Swimrite Manufacturing Co., Inc., Van Nuys, Calif., a corporation of California

Filed Nov. 20, 1967, Ser No. 9,474

Term of patent 14 years

(Cl. D23—3)

I claim:

The ornamental design for a filter, substantially as shown.
